APPARATUS FOR SIZING TUBING

Filed March 14, 1950

UNITED STATES PATENT OFFICE

2,585,450

APPARATUS FOR SIZING TUBING

Bernard E. Frank, Rochester, N. Y., assignor to
 General Motors Corporation, Detroit, Mich., a
 corporation of Delaware

Application March 14, 1950, Serial No. 149,563

2 Claims. (Cl. 153—80.5)

1

This invention relates to apparatus for sizing the end portion of a length of tubing. In an apparatus of this kind used heretofore, a length of tubing is gripped between clamps while the sizing punch is caused to be moved into the end of the tubing to expand the end portion to the required diameter. The extent to which the portion of the end tubing is sized or flared is dependent upon the distance between the end of the tubing and the sizing punch in its fully retracted position and upon the stroke of the punch.

An object of the present invention is to provide apparatus for sizing the end portion of a piece of tubing regardless of the distance, within certain limits, between the end of the tubing and the punch in its retracted position, thereby avoiding the necessity of accurate location of the end of the tubing in order that the length of the sized or flared portion of the tubing will be uniform.

Further objects and advantages of the present invention will be apparent from the following description, reference being had to the accompanying drawings, wherein a preferred embodiment of the present invention is clearly shown.

In the drawings:

Fig. 1 is a plan view of the sizing apparatus involving the present invention.

Fig. 2 is a sectional view on line 2—2 of Fig. 1.

Figs. 3 and 4 are views similar to Fig. 2, showing the apparatus in different operating positions.

Figs. 5, 6 and 7 are sectional views, respectively, on lines 5—5, 6—6 and 7—7 of Fig. 2.

The apparatus comprises a cylindrical frame member 10 adapted to be received within the cylindrical bore of a guiding member (not shown) and having a threaded hole 11 for receiving a threaded coupling member (not shown) which connects the frame 10 with an operating mechanism such as a piston located in a cylinder which receives pressure fluid to cause the frame 10 to be advanced and retracted relative to the tubing. Frame 10 has a central cylindrical bore 12 which receives and guides a bar 13 having a cylindrical portion 14 having a sliding fit with the bore 12. Bar 13 has a longitudinal rib or key portion 15 received by a longitudinal groove 16 in frame 10 whereby rotation of bar 13 relative to frame 10 is prevented.

The bore 12 of frame 10 receives a block 17 which is generally of cylindrical contour and which has an air venting groove 18 and a groove 19 receiving that portion of the rib 15 which is

2

above the groove 16 of frame 10. Thus the block 17 which has a sliding fit within the frame 10 is prevented from rotating.

Block 17 has a threaded bore coaxial with frame 10 which receives a screw plug 20 and a threaded shank 21 of a sizing punch 22 having a sliding fit with the central bore in the cylindrical portion 14 of bar 13. The plug 20 and the shank 21 are screwed into the block 17 as far as they will go. The plug 20 may be one of several different lengths determined in accordance with the required normal distance between the left end of the bar 13 and the left end of punch 22. To adapt the apparatus for a particular sizing operation, a plug 20 of the required length is selected. To prevent unscrewing of the punch 22 relative to block 17, a set screw 23 is tightened to force a soft metal plug 24 against the threaded shank 21 of punch 22.

20 A spring 25 surrounding punch 22 and confined under compression between block 17 and portion 14 of the bar 13 urges said bar to the left, said motion being limited by engagement of portion 14 with a plate 26 which screws 27 secure to frame

25 10. Spring 25 urges block 17 to the right into engagement with a roller 30 journaled on a pin 31 carried by a lever 32 journaled on a pin 33 supported by frame 10. A pin 34 supported by frame 10 retains a torsion spring 35 having one end 36 connected with frame 10 and an end 37 connected with lever 32. Spring 35 urges lever 32 counterclockwise and roller 30 into engagement with an upper surface of portion 15a of rib 15.

35 Usually the tube T is clamped in a fixed position and the frame 10 is moved. However, the frame 10 can be fixed and the tubing can be moved axially by moving the grippers. In the following explanation of the mode of operation 40 of the apparatus, the frame 10 is considered fixed and the tubing T axially movable. Let it be assumed that, initially, the right end of tubing T is in the position shown in Fig. 2. As tubing T moves to the right relative to frame 10, the punch

45 enters it since, at first, the punch cannot move right because right movement of block 17 is obstructed by a device including the roller 30 and lever 32 when located as shown in Fig. 2. It is apparent that during the first part of relative movement between the tubing and the frame 10, the tubing has engaged the part 14, which serves as an abutment and has moved the bar 13 from the position shown in Fig. 2 to that shown in Fig. 3. At the end of said first part of this relative movement, the rib 15 of the bar 13 has cam-

med roller 30 from the position shown in Fig. 2 to that shown in Fig. 3 due to engagement with roller 30 by an inclined camming surface 15b of rib 15. During this movement of roller 30, it has moved away from end surface 17a of block 17 (at right angles to its direction of movement) into engagement with oblique surface 17b, thereby causing the force exerted by spring 35 against the surface 17b, to the roller 30 to be on a center line represented by the dot-dash line 40 which is at right angles to surface 17b and intersects the point of tangency of surface 17b and roller 30. Since this center line is substantially above the pivotal axis of the lever 32 at the center of pin 33, spring 37 is overcome and lever 32 is caused to move from the position shown in Fig. 3 toward the position shown in Fig. 4, as tubing T moves from the position shown in Fig. 3 to the position shown in Fig. 4.

During this movement of the lever 32, there is no relative movement between punch 22 and bar 13. Therefore the distance between the left end of punch 22 and the left end of abutment portion 14 of bar 13 remains unchanged. It is therefore apparent that the extent to which the tubing T receives the punch 22 is determined by two factors, namely, the distance to which the punch 22 normally extends to the left of the abutment portion 14 of the bar 13 and the distance through which bar 13 moves to cam the roller 30 from the position shown in Fig. 2 to that shown in Fig. 3. Therefore the initial distance between tubing T and the punch 22 can vary to an extent equal to that displacement of bar 13 relative to frame 10 which takes place to cause cam 15b to move roller 30 from normal position shown in Fig. 2 in which it prevents relative movement between block 17 and frame 10 to the position shown in Fig. 3 in which the function of roller 30 is nullified. The operation of the parts described would be the same whether the relative movement between the punch 22 and the tube T is effected by a reciprocatory movement of the frame 10 which carries the punch 22, or of the tube. Obviously, this reciprocatory movement of the frame 10 or the tube T will be sufficient to size pieces of tubing uniformly although the initial distance between the punch and the tubing may vary to the stated extent.

Whether the frame 10 is advanced to the left relative to the tubing T and is retracted to the right or the tubing is advanced to the right and retracted to the left, Figs. 3 and 4 show relative positions of parts of the punch apparatus during advancement thereof. Relative retraction between the frame 10 and the tubing causes return of parts to the normal positions shown in Figs. 1 and 2.

During a first part of the retraction of frame 10, the punch 22 remains in engagement with the tubing T while frame 10 moves into such position that spring 37 can return roller 30 to a position upon the upper surface of rib 15. During further retraction of the frame 10, a pin 38 carried by the frame engages block 17 to cause removal of the punch 22 from the tubing T and spring 25 is permitted to expand to press block 17 against roller 30 and the abutment 14 of bar 13 against plate 26. As bar 13 moves left relative to frame 10, cam surface 15b of rib 15 moves left relative to roller 30 and spring 37 forces roller 30 against surface 15a of rib 15, spring 25 having lost compression to the extent that spring 37 is able to perform this function.

While the embodiment of the present inven-

tion as herein disclosed, constitutes a preferred form, it is to be understood that other forms might be adopted.

What is claimed is as follows:

1. A sizing punch apparatus for use with a tube flaring machine having a tubing gripper and a mechanism for effecting relative advancing and retracting movements between a sizing punch and the tubing retained by the gripper, said apparatus comprising a frame, a bar supported by the frame for movement longitudinally of the tubing and having an abutment portion for engagement by the tubing, a block supported by the frame for relative movement longitudinally of the tubing and spaced from said abutment, a punch attached to the block and extending therefrom through the abutment a certain distance from the surface of the abutment facing the tubing, yielding means transmitting motion from the bar to the block, a device carried by the frame and normally conditioned for preventing relative movement between the block and frame whereby, during relative movement between the frame and the tubing, a portion of the punch is received by the tubing before engagement between the tubing and the abutment and then the abutment is moved relative to the block as an additional portion of the punch is received by the tubing, means actuated in response to said movement of the abutment relative to the block for rendering said device unable to prevent relative movement between the block and frame whereby reception of the punch by the tubing ceases as advancement of the frame continues, and means provided by the frame for engaging the block during relative retraction between the frame and tubing in order to remove the punch from the tubing.

2. A sizing punch apparatus for use with a tube flaring machine having a tubing gripper and a mechanism for effecting relative advancing and retracting movement between a sizing punch and the tubing retained by the gripper, said apparatus comprising a frame, a bar supported by the frame for movement longitudinally of the tubing and having an abutment for engagement by the tubing, a block supported by the frame for movement longitudinally of the tubing and spaced from said abutment, a punch attached to the block and extending therefrom through the abutment a certain distance from the surface of the abutment facing the tubing, a helical coil compression spring surrounding the punch and confined between the abutment and the block to urge them apart, a stop attached to the frame and normally engaged by the bar to resist separation of the bar from the block, means for normally opposing separation of the block from the abutment and comprising a lever pivotally supported by the frame and a roller carried by the lever, said block having an end surface at right angles to the direction of relative movement between the punch and the tubing, said end surface being normally engaged by the roller, said block having a surface inclined from the plane of the first mentioned surface and away from the lever, a second spring normally holding the lever in position such that the roller is engaged by the first mentioned surface of the block, a cam provided by the bar for moving the roller against the action of the second spring from normal position to a position in which the roller engages the inclined surface of the block, whereby the leverage of the force which the first spring applies to the lever increases to a value such that the second spring is overcome by the first spring and

the roller ceases to retain the block, said cam functioning during a certain movement of the bar abutment relative to the punch, and means provided by the frame for engaging the block during relative retraction between the frame and the tubing in order to remove the punch from the tubing.
